DESIGN FOR A CASKET

Harry A. Neff, Bellaire, Ohio, assignor to The Belmont Casket Mfg. Company, Columbus,
Ohio, a corporation of Ohio

Application January 3, 1935, Serial No. 54,710

Term of patent 14 years

To all whom it may concern:

Be it known that I, Harry A. Neff, a citizen of the United States, residing at Bellaire, in the county of Belmont and State of Ohio, have invented a new, original, and ornamental Design for a Casket, of which the following is a specification, reference being had to the accompanying drawing, forming a part thereof.

In the drawing:

Figure 1 is a side elevation of a casket showing
my new design;

Figure 2 is an end elevation thereof;
Figure 3 is a fragmentary side elevational view
upon a larger scale for the purpose of more clearly bringing out detail.

I claim:
The ornamental design for a casket substantially as shown.

HARRY A. NEFF.
